POCKET KNIFE

Oswald von Frankenberg und Ludwigsdorf, Landwehrstr. 73, Solingen auf der Hohe, Germany
Filed Mar. 1, 1961, Ser. No. 92,496
1 Claim. (Cl. 30—156)

This invention relates to a pocket knife and more particularly to a hunting pocket knife having instruments capable of being swung out, such as blades, saws, or the like.

In conventional pocket knives one or more knife-blades are arranged in one single knife box, each in its own compartment together with a retaining spring. These blades are swivel jointed on the front end of the knife box so that, by means of the pressure of the springs, the blades and other instruments of the knife are kept intact within the box portion. The retaining spring of any blade or blades, as well as other instruments of the knife, exerts some pressure at all times, and is held in place by means of rivets.

As is well known, the pocket knives and particularly hunting pocket knives become dirty after they are used for some time; and if the dirt penetrates through the inner grooves of the knife, cleaning becomes difficult and often impossible. Especially in the case of hunting pocket knives which are used in cutting wild meat deposits of dirt build up between the springs and in the compartments of the knife-box. Running water may not remove this dirt. After the blades are used for some time, they get very hard to work with; and when open, they do not keep in place, so that the working value of the blades and other parts of the knife diminishes greatly.

It is an object of this invention to devise a pocket knife which can be disassembled easily, cleaned and reassembled without using special instruments and tools.

The main difficulty encountered is the devising of a retaining spring for the knives, which is not only easily releasable, and can be taken out from the knife, but also one that after reassembling the instruments will provide the same tension as before.

Already several kinds of pocket knives exist in which the blades are fastened to but releasable from the handle, whereby the blades can be replaced when broken. In most of these constructions, however, the retaining springs are riveted firmly in the handle portion of the knife and it is necessary to replace the rivets as well as the blade.

In an embodiment of the present invention the retaining spring is a separate element and is placed loosely in the knife box so that there will be no lengthwise movement in the base of the knife box. A removable lever arm is suspended on a swivel joint fixed in the knife box such that the lever arm bears against the retaining spring and holds it in place. The lever arm compresses the retaining spring when the lever arm is in its seated position and releases all pressure on the spring in its open position so that the elements may be disassembled and reassembled without contending with pressure from the retaining spring.

The foregoing and other objects, features and advantages of the invention will be apparent from the following more particular description of preferred embodiments of the invention, as illustrated in the accompanying drawings.

FIG. 1 is a side view of a hunting pocket knife in accordance with the invention;

FIG. 2 is a top view of the knife of FIG. 1;

FIG. 3 is a cross-sectional view of the knife of FIGS. 1 and 2;

FIG. 3a is a cross-sectional view of a modification of the knife of FIG. 1;

2

FIG. 4 is a longitudinal sectional view of the knife seen in FIG. 1;

FIG. 5 is another longitudinal sectional view of the knife of FIG. 1;

FIG. 6 is a top view of the empty knife-case of FIG. 5;

FIG. 7 is a side view of the knife blade of FIG. 1;

FIG. 8 is a side view of the saw-blade of FIG. 1;

FIG. 9 is a side view of the bolt member used as a swivel-axis for the blade and saw;

FIG. 10 is a side view of a middle-plate member which is placed between the blade and saw to prevent contact of the two parts;

FIG. 11 is a side view of the bolt lever;

FIG. 12 is a top view of the bolt lever;

FIG. 13 is a side view of the composite retaining spring made up of three single springs, in which the single springs are cut with distinguishable different angles, to show the contours clearly; and

FIG. 14 is a top view of the composite retaining spring.

The hunting knife shown in the view of FIG. 1 comprises a handle 1, which is made of a single-part die-cast material to form a knife case 2. The handle shells 2a and 2b are riveted on the sides of the knife

case 2. On the front end of the knife case there are two jaws 3a and 3b, between which the knife blade 4 and the saw blade 5 can swing open around the swivel axis comprising the screw 6. The blade 4 has a fine sawtooth construction near one end, and the saw 5 has a screw lever blade construction on its tip. The saw-teeth 5b on blade 5 are made in two opposite rows next to each other to provide a cut both ways. On the lower side of the saw blade 5, there is a bottle opener 5c. It is clear that instead of the knife blade 4 and the saw blade 5, one could substitute any other swivel-jointed instrument.

FIG. 2 shows how the knife blade 4 and the saw blade 5 lie beside each other in the knife case with relatively thin side walls.

40 The releasable assembly of the knife blade 4 and the saw blade 5 between the jaws 3a and 3b can be observed in FIG. 3. Here the screw 6 whose shaft 6a forms the swivel axis of the blade and the saw is only provided with threads 6b on the outer end. The screw can be turned by means of the threads into the jaw at 3b.

45 The ends 4b and 5d of the blade 4 and the saw 5 are placed on the smooth shaft 6a of the screw 6. Between these ends and the bottom 2d of the knife, three spring sections 7a, 7b and 7c are placed; and to prevent any friction action between the ends of the knife blades, a middle plate 8 made of brass is placed between the blade ends.

50 FIG. 3a shows another embodiment of the invention. Here a shaft 9 is mounted on the shaft 6a of the screw 6, which for instance could be pressed in the end of the knife blade 4 and make swivel surfaces for the saw 5.

If one desired to obtain a larger swivel diameter, he could instead of the shaft 9, make the screws 6 have a correspondingly larger diameter. This way, the re-

60 assembly of instruments on the swivel joint will be made easier. Besides, a lock-nut 10 can be inserted in the jaw 3b, so that the screw 6 can be pulled up from both sides through the jaws 3a and 3b. The slits in the screw 6 and in the lock-nut 10 are so formed, that one 65 can loosen or fasten the screws or the lock-nut with an ordinary coin.

The length wise section in FIG. 4 shows the position of the retaining spring, the underside of which is slightly convex and also the position of the lever arm 18 in the knife case 2, when the blade 4 is completely open and the saw 5 is closed.

The retaining spring 7, consisting of three spring sec-

tions, joined together by a joint rivet **7d**, has a cross-groove **11** in the middle position, which passes through all three sections. A peg **12** in the knife case **2** is hooked in this groove. The groove **11** and the cross peg **12**, both prevent any axial slipping of the retaining spring inside the knife case. The middle section **7c** of the retaining spring **7** has a right-angular lock tip on its front end, with which this section hooks in a flat locking groove **14** of the blade end **46**, and so the blade is kept fixed and firm in the swung-out position.

The lever arm **18** has a groove **15** which is open on top and rather right-angular. With this groove, the lever arm is hooked on the cross peg **16** which passes through the knife casing. The cross peg **16** forces the front end of the lever arm **18** to lie tightly on the backward end of the retaining spring. The lever arm **18** has a trigger cam **17** under its swivel joint **15** and **16**. The cam is shaped like a club, and as shown in FIG. 4 presses the back end of the retaining spring **7** to the base of the knife box **2**. The lever arm has an angular tip on the back which is turned up, and whose end is bent horizontally. It braces itself on the back end of the knife box when the lever is in tension. The tip **18b** may help, by means of a small recess in the outer side of the end plates, to turn up the lever **18**.

FIG. 5 is a representation of the corresponding lengthwise section through the handle **1** of the hunting knife. Here the saw **5** is completely open, so that the front end of the retaining spring lamina **7c** can lie on the resting plate **20** of the end **5d** of the saw **5**, and thereby can hold the open saw firmly in place. The trigger cam **17** of the lever **18** presses the back end of the retaining spring firmly to the base of the knife box.

FIG. 6 shows the peg **12** shaped on the base **2d** of the knife box **2** as well as the cross peg **16** for the lever arm **18**. The knife box **2** is a one piece diecast material preferably brass, so that it needs no further internal or external working.

After casting it is only necessary to rivet the cross peg **16**, and provide certain holes in the jaws **3a** and **3b** for the swivel axis **6a** and also some additional holes **21** for the rivet-fixtures of the handle shells **2a** and **2b**.

FIG. 7 shows the knife blade **4** with its end **4b**, the recess **14** and the flat resting plate **22** where the front end of the retaining spring section is located when the blade is closed.

FIG. 8 shows the saw **5** taken out of the knife with the resting places **20** and **23** for the front end of the retaining spring which holds the saw **5** in open or closed position firmly.

FIG. 9 shows a component representation of the screw **6** serving as the swivel axis with its smooth shaft **6a** and its threads **6b**. Next to this screw, there is a nut **6c**, which is used when no threads are to come into contact with the jaws of the knife box.

FIG. 10 shows the middle plate **8** which is placed between the ends of the knife blade **4** and the saw **5** and which hooks or clamps between the neighboring end surfaces of the retaining spring sections **7b** and **7c** in a recess or slit **24** (refer to FIG. 14) by means of the tip **8a**.

The lever arm **18** shown in FIGS. 11 and 12 has a width which corresponds with the inner diameter of the knife box **2**. Only the tip **18a** is angled out more narrow. This representation shows the formation of the trigger cam **17** more completely. The slot **15** enables the lever **18** to be suspended over the cross peg **16**.

It would be possible, in a knife with only one blade, to use a one piece retaining spring. Since in a hunting pocket knife a special lock spring is favorable in order to keep the knife blade firmly in the open position and, since two or more blades or instruments must be provided, use is made of a three part retaining spring consisting of three sections **7a**, **7b** and **7c** held together by the rivet **7d**. These sections can swing beside each other about the rivet **7d**.

The section **7a** shown in FIG. 13 serves to hold the knife blade **4** firmly in the closed position thus the front end of this lamina is made smooth. The second section **7b** holds the right angular tip **13** which serves as the lock tip for the open knife blade and clips in the right angular resting **14** in the end **4b** of the knife blade **4**. The section **7c** is smooth on its front end and serves only to hold the saw **5** firmly in the opened and closed positions. It is appropriate to mention in FIG. 13 and 14 a cross peg **25** fixed on the middle section **7b** in the raised end **26**. This peg on the upper edge of the sections when they are flat together.

The section **7c** lies under the saw **5**, which even in the closed position is not firmly stopped, so that it can still be pressed further in the knife box by a slight pressure. Saw blade **5** presses at **5e** (FIG. 4) on the peg **25** and pushes down the section **7b** along with the tip **13** so much in the middle that the right angular tip **13** comes out of the resting **14** at the end **4b** of the knife blade **4**. This way the knife blade **4** in the open position is raised out of locked position so that the knife blade **4** can be closed after the pressure on the saw blade **5**.

In order to disassemble this pocket knife into its basic parts when it has become dirty, the following simple steps are taken: First, the knife blade **4** as well as the saw blade **5**, are flipped open. The lever arm **18** is raised at the end **18b** of the tip **18a** so that the lever assumes a somewhat vertical position. In this position the pressure of the cam **17** acting on the back end of the retaining spring **7** is released. Also, the spring pressure on the ends of the knife blade **4** and the saw **5** is cancelled. Later on the lever arm **18** can be removed easily from behind the cross peg **16** in the vertical position then it becomes completely free and can be cleaned. Since the pressure of the retaining spring **7** is removed from the ends of the knife blade and the saw, the screw **6** can be loosened and pulled out through the jaws of the knife box **2** so far that the knife blade **4**, the saw **5** and the middle plate **8** can be pulled out easily from above or front. Later these pieces can be individually cleaned. After that the knife box **2** is turned over and the retaining spring **7** will either come off by itself or can be pushed out from the knife box **2** easily. This completes the disassembly of the pocket knife.

After cleaning the single parts, the retaining spring **7** is pushed from the open front of the box so far inside that the slot **11** rests over the cross peg **12** on the base of the knife whereby the longitudinal motion of the retaining spring is prevented. Then the knife blade **4**, the middle plate **8** and the saw **5** are so placed together that the holes of these three parts match each other. These three parts are replaced from the top or from the front in the open front end of the knife box. They are pushed in toward the front end of the retaining spring **7** until they stop. In this position the holes of the three parts get close to the holes made in the jaws **3a** and **3b** of the knife box so that the screw **6** with its slightly smaller diameter can be inserted. In this position of the parts, the back end of the slightly curved retaining spring is lifted somewhat. After inserting the vertically held lever arm **18** over the back end **7e** of the spring **7**, the lever can slip with its slot **15** over the cross peg **16** then the lever **18** is turned up so that its trigger cam **17** presses the back end **7e** of the retaining spring **7** on the base **2d** of the knife box **2** and, thereby, pushes all the three sections of the retaining spring **7** so that their front ends press on the ends of the knife blade **4** and the saw **5**. Here the cam **17** of the lever **18** goes above a dead point. This cam lies in the final pressure position of the lever **18** (refer to FIGS. 4 and 5) somewhat directly under the middle line of the cross peg **16**. The end **18b** of lever arm tip **18a** is placed on the upper edge of the back wall **2c** of the knife box **2**. Now the saw **5** can be flipped in the knife box. By means of a slight pressure on the end of the saw **5** the section **7b** of the knife blade **4** on the peg

25 can be pushed out in the same way already described so that this blade also can be flipped back in the knife box.

From the foregoing description it will be seen that the assembly as well as the disassembly of the knife is quite simple. The disadvantageous results of the dirt which cannot be removed without much trouble in conventional pocket knives can be overcome in the case of these knives even without using many tools.

While the invention has been particularly shown and described with reference to a preferred embodiment thereof, it will be understood by those skilled in the art that various changes in form and details may be made therein without departing from the spirit and scope of the invention.

What is claimed is:

A pocket knife capable of being disassembled for cleaning comprising a unitary case member, a blade member, means for detachably mounting the blade member for operation to and from a closed position within the case member, a transverse projection within said case member, a plurality of spring members fastened together for movement about a common pivot point and loosely

5 mounted within the case member in engagement with said transverse projection for holding the blade member in open and closed positions of operation, pin means extending transversely of said case member intermediate said common pivot point and said transverse projection, and detachable lever means pivotally mounted under said pin means in engagement with said spring members and said case member, a portion of said detachable lever means extending exteriorly of said case member in position to be

10 grasped readily when disassembly is desired.
